LABEL APPLYING MACHINES

George W. von Hofe, Bound Brook, N. J., assignor to New Jersey Machine Corporation, Hoboken, N. J., a corporation of New Jersey

Application February 11, 1953, Serial No. 336,261

11 Claims. (Cl. 216—55)

This invention relates to label applying machines and particularly to that class of labeling machines in which the labels are fed from a source of supply to a label applying station at which they are placed upon articles and then subjected to the action of a pressure device to complete their application to the articles.

An object of the invention is to provide an improved labeling mechanism capable of reducing the period of label application to enable an increase in the feeding time of the labels without slowing down the machine or to enable a substantial increase in the production of the machine without reducing the feeding time of the labels.

Another object of the invention is to provide an improved labeling mechanism capable of removing entrapped air from under the label during the application of pressure to the latter so as to secure perfect adhesion of the label to the article.

A further object of the invention is to provide an improved labeling mechanism capable of applying pressure to the label immediately after it has been placed on the article.

A still further object of the invention is to provide an improved labeling mechanism capable of applying a high pressure to the label without increasing the power used in the machine and without applying high forces to the article being labeled.

Other objects and advantages of the invention, as well as the novel features thereof will appear from a perusal of the following description when read in connection with the accompanying drawings in which—

Fig. 1 is a fragmentary side elevational view of a label applying machine embodying the invention, and

Fig. 2 is a front elevational view of some of the parts shown in Fig. 1.

In the following description the use of the term "label" is intended to include any sheet of material which is to be deposited on an article for the purpose of identifying the contents thereof, or for any other purpose. The label may have any desired form and may have thereon any suitable type of adhesive material for adhering it to the article. Also the labels may be fed from a continuous web or from a supply of individual labels, as is well known in the art. In accordance with the invention, the labels are fed from the source of label supply to the article support 10 by means of a pick-up device of the suction-operated type which is designated generally in the drawings by the numeral 11. After a label has been deposited upon the article 12 positioned on support 10, pressure mechanism designated generally by the reference numeral 13 comes into operation to complete the adhesive application of the label to the article. In general the machine in which the aforesaid devices are embodied may be of any well-known type, but modified in accordance with the present invention. For the purposes of illustrating the invention, such devices have been shown as embodied in a labeling machine, such as is described and illustrated in the von Hofe Patent No. 2,227,816 issued January 7, 1941. In such a machine

there is provided a carriage 14 (see Fig. 1) slidably mounted on a horizontal guide rail 15 supported on the frame of the machine. The carriage 14 is reciprocated lengthwise of the rail 15 in predetermined timed sequence by mechanism exemplified in Fig. 1 of the drawings by the rod 16 which is pivotally connected at 17 to the carriage. A member or plunger 18 is slidably mounted on the carriage 14 and is vertically reciprocated thereon in properly timed relation with the associated parts by mechanism exemplified in Fig. 1 of the drawings by the roller 19 which is adapted to travel along a horizontally extending track 20 arranged to be raised and lowered to reciprocate the member 18. The downward movement of the member 18 may be facilitated by a vertically disposed spring 21 which is connected at its lower end to the carriage 14 and at its upper end to a lug 22 on the member 18. Secured to the lower end of the member 18 through a yoke 33 is the label carrier or transporting device 11.

It will be understood from the parts of the labeling machine thus far described, that when in the operation of the machine, the parts are positioned as shown in Fig. 1, a label 23 has just been deposited by the carrier 11 upon the article 12 and the track 20 has been raised to lift the member 18 and consequently the label carrier 11 away from the article. The label carrier 11 is of the suction type and is connected by tube 34 with a convenient source of suction which is controlled by properly timed valving means of any suitable type so that suction is effected at the label carrying surface 24 of such device, while it is picking up a label from the source of label supply and until the label carried thereby has been deposited on the article 12. In the position of the label carrier 11 shown in Fig. 1 of the drawings, the suction thereto has been cut off by such valving means. From its position in Fig. 1 of the drawings, the label carrier 11 is retracted by the carriage 14 which is caused to move to the right, as viewed in Fig. 1 of the drawings. When the carriage 14 reaches the right-hand limit of its movement along the rail 15, the label carrier 11 will be located above and in registry with the next label at the source of label supply to be delivered to a succeeding article to be labeled. The movable rail 20 will then be lowered to enable the label carrier 11 to pick up such label. At this time suction is again effected at the label supporting surface 24 of the carrier 11. When a label 23 has been picked up by the carrier 11, the track 20 is again raised to elevate the member 18 and consequently the label carrier 11. The carriage 14 is then caused to move to the left, as viewed in Fig. 1 of the drawings to bring the label carrier 11 over the article 12 mounted on the support 10 in label receiving position. The track is then again lowered and the member 18 moves downwardly on the carriage 14 thereby causing the label carrier 11 to deposit the label 23 carried thereby upon the article 12. To enable this to be accomplished, the valving means operates to discontinue the suction in the label carrier 11. When the disposition of the label has been completed, the label carrier 11 is lifted by the action of track 20 on the roller 19 and member 18, thus bringing these parts back to the positions shown in Fig. 1 of the drawings, to repeat the operations above described.

After the deposition of a label 23 on the article 12, a roller 25 of the pressing mechanism 13 is lowered to the dotted line position shown in Fig. 1 of the drawings, to enable it to press the label onto the article 12 as the carriage 14 retracts the label carrier 11 to the label supply station to receive a new label in the manner above described. As shown in the drawings, the roller 25 is rotatably mounted on a shaft 26 supported at its ends on the offset, downwardly extending end portions of a pair of spaced arms 27, 27. The other ends of arm 27, 27, are

pivotedly connected by stub shafts 28, 28, to spaced blocks 29, 29 mounted on the carrier 11. Adjacent to the offset end portions of the arms 27, 27, the arms are connected together by a tie-rod 30 which maintains the free ends thereof in proper spaced relation. The free ends 5 of arms 27, 27, and consequently roller 25 are normally maintained in raised positions by springs 31, 31, which are connected at their lower ends to such arms intermediate the stub shafts 28, 28, and the tie-rod 30 and at their upper ends to brackets 32, 32, secured to the yoke 33 which connects the label carrier 11 to the member 18.

When the label carrier 11 is positioned in the region of the label applying station as shown in Fig. 1 of the drawings, rollers 35, 35, rotatably mounted on the free ends of arms 27, 27, engage the underside of a plate 36 secured to the lower end of a shoe 37, as by bolts 38. The shoe 37 is mounted on the lower end of a plunger 39 vertically slidably in a guideway 40 suitably supported on the frame of the machine. The plunger 39 may be vertically reciprocated in the guideway 40 in properly timed relation with the other elements of the machine by mechanism, such as is described and illustrated in the aforesaid patent, No. 2,227,816, and exemplified in Fig. 1 of the drawings by the lever 41 which preferably has its rounded free end projecting into a slot 42 at the upper end of plunger 39 and engaging the upper end of such slot and a yieldably mounted member 43 carried by a block 44 secured to the plunger 39. When the plunger 39 moves downwardly in its reciprocal movements, the plate 36 through the rollers 35, 35, will cause the arms 27, 27, to move downwardly about their shafts 28, 28, to move the roller 25 from the full line position shown in Fig. 1 of the drawings, to the dotted line position thereof. Thus, as the carriage 14 retracts the label carrier 11 to receive another label, the roller 25 will press the label 23 deposited on the article 12 firmly and evenly on the latter. During this following movement of the roller 25, the rollers 35, 35, will rotate along the underside of the presser plate 36 to the end thereof and then will roll off such plate as the carrier continues its movement to the place of label supply. The presser plate 36 may be made of varying lengths to maintain the roller 25 depressed for varying periods depending upon the lengths of the labels to be applied to the articles, or the plate may be adjustably mounted on the shoe 36, as indicated in the drawings, to enable it to be adjusted lengthwise of the path of movement of the label carrier 11, to obtain the same results with a standard sized plate.

From the foregoing description of the parts, it is believed it will be understood that after the label carrier 11 has picked up a label at the label supply station and is moving to the left, as viewed in Fig. 1 of the drawings, to a position over the article to be labeled, the roller 25 is in a fully retracted position under the influence of the springs 31, 31, and the plunger 39 is in a raised position. As the carrier 11 continues its movement to the left, the rollers 35, 35, come into engagement with the right-hand end of plate 36 and are slightly depressed as they roll into engagement with the underside thereof. The right-hand end of plate 36 is preferably beveled on its under surface to facilitate the engagement of the rollers 35, 35, therewith. During the continued advancing movement of carrier 11, the rollers 35, 35, will roll across the plate 36 with the roller 25 in a substantially fully raised position. At the end of the advancing movement of carrier 11, it is lowered and raised by the track 20 in the manner previously explained to deposit the label carried thereby upon the article 12, and to bring it to a position to be longitudinally retracted by the carriage 14 on the return movement of the latter. This point in the operation of the parts is illustrated in full lines in Fig. 1 of the drawings. When the carriage 14 starts its return movement to the right along the rail 15 to retract the label carrier 11 to the label supply station, the lever 41 will be rocked downwardly on its shaft to shift the plunger 39 downwardly. This causes the shoe 37 and plate 36 to move downwardly, 70

the latter through the rollers 35, 35, causing the arms 27, 27, to be rocked downwardly about the axis of shafts 28, 28, to bring the roller 25 down to the dotted line position shown in Fig. 1. The rocking of lever 41 is so timed that the roller 25 is in its lowermost position immediately after the carrier 11 has started its return movement, and before the carrier 11 has been retracted sufficiently to bring roller 25 over the portion of the bottle to which the label has been applied. As the carrier 11 continues its retraction movement, the lever 41, plunger 39 and roller 25 are maintained in their lowered positions, the roller 25 rolling upon the label to iron it to the surface of the article 12. During the progressive advancement of the roller 25 over the label, its force will be applied along a line contact, thereby subjecting the label to a substantially greater ironing pressure than could be applied by a pressure plate using the same force. This progressive application of force also accomplishes a squeegee action to remove any entrapped air from between the label and the article, and thereby avoids the possibility of blisters forming under the label. The roller 25 can be made sufficiently wide to take care of the widest label to be used in the operation of the machine, thereby also avoiding the necessity of changing parts for different sized labels. After the roller 25 has completed its rolling operation on the label, the lever 41 is rocked to raise plate 36, thereby permitting arms 27, 27, to be pivoted upwardly by springs 31, 31, to raise roller 25. As the label carrier 11 continues its movement to the right, the rollers 35, 35, will roll off the plate 36 thereby enabling the springs 31, 31, to lift the roller 25 to the top of its range of movement about the axis of shafts 28, 28. The operations above described are repeated in operative sequence throughout a given operative period of the machine.

The article support 10 comprises a base or article rest 50 provided with two sides 51, 51, and a back wall 52; such sides and back wall providing a means for proper registration of the article with relation to the label applying mechanism of the machine so as to obtain proper positioning of the labels on the articles. It will be noted that the depth of the sides 51, 51, and wall 52 is less than the height of the article so that they will not interfere with the label applying operations. At least one of the walls 51 however, is provided on its forward end with a guide rail 53 having its upper surface substantially flush with and in advance of the surface portion of the article to which the label is to be applied. Thus, when the roller 25 is initially depressed, it comes into engagement with the top surface of the guide rail 53, and as the label carrier is retracted, the roller 25 is started rotating before it comes into contact with the label. As a result of this arrangement, any danger of the label shifting on the article when the roller 25 comes into engagement therewith, is eliminated. The article support 10 is preferably mounted on means whereby exact registration of the article with relation to the labeling mechanism may be obtained. As shown in the drawings, such means includes a slide 54 which supports the base 50 of the article support, and which is mounted for slidable movement in the direction of longitudinal movement of the carrier 11 on a plate 55. Adjustment of slide 54 relative to plate 55 is obtained by manually manipulating hand wheel 56 which contacts a suitable worm gear arrangement provided in a manner known in the art, between the slide 54 and plate 55. Plate 55 is mounted on a slide 57 which is slidably mounted on plate 58 for movement in a direction transverse to the direction of movement of slide 54. Slide 57 may be adjusted relative to plate 58 by manipulating the hand wheel 59 which controls a suitable worm gear arrangement. Plate 55 may be supported in any suitable manner upon the frame of the machine.

While I have hereinabove described and shown in the drawings a preferred embodiment of my invention, it will be apparent to those skilled in the art that various changes and modifications thereof may be made without departing

from the spirit of the invention or the scope of the appended claims.

I claim:

1. In a labeling machine, means to support an article to be labeled, a label carrier for delivering a label to an article on said support, a device mounted on said carrier for pressing the label delivered to the article into firm contact with the latter, said device including a rotatably mounted roller and means normally supporting said roller on said carrier, a movable track, a roller carried by said movable supporting means coacting with said track, and means for moving said track to move said track roller and said movable supporting means to advance said pressing roller into label pressing position and to apply pressure to said pressing roller during the pressing of the label on the article.

2. In a labeling machine, means to support an article to be labeled, a label carrier for delivering a label to an article on said support, a device mounted on said carrier for pressing the label delivered to the article into firm contact with the latter, said device including a rotatably mounted roller and means movably supporting said roller on said carrier, a movable plate, a roller carried by said movable supporting means and engageable with the underside of said plate, and means for depressing said plate and through said plate roller to cause said movable supporting means to advance said pressing roller into label pressing position and to apply pressure to said pressing roller during the pressing of the label on the article.

3. In a labeling machine, means to support an article to be labeled, a label carrier for delivering a label to an article on said support, horizontally movable means for pressing the label delivered to the article into firm contact with the latter, a vertically operated slider having a pressure member engageable with said horizontally movable means to bring the latter into label pressing position, and means to operate said slide to cause said pressure member to depress said horizontally movable means into said position during a portion of the horizontal movement of the latter.

4. In a labeling machine, a labeling station, means for delivering a label to said labeling station for the label to be adhesively connected to the article to be labeled at said station, a movable rotatably mounted roller for pressing the label to the article at said station, means to advance said roller into contact with the label connected to the article and to roll the same across the surface of the label, means to start the rotation of the roller prior to its engagement with the label, and means to apply pressure to the roller during its travel across the label.

5. In a labeling machine, a labeling station, means for delivering a label to said labeling station for the label to be adhesively connected to the article to be labeled at said station, means at said station for registering an article in proper relation to said label delivery means, a movable rotatably mounted roller for pressing the label to the article at said station, means to advance said roller into contact with the label connected to the article and to roll the same across the surface of the label, means carried by said registering means and engageable by said roller during its advancing movement to start the rotation of the roller prior to its engagement with the label, and means to apply pressure to the roller during its travel across the label.

6. A labeling machine such as defined in claim 5, in which said registering means includes an article support and adjustable means for varying the position of said support, and in which the means for starting the rotation of the roller consists of a track member engageable by said roller, said track member being mounted on said article support.

7. In a labeling machine, a support for an article to be labeled, a label carrying device, means for moving said device to carry a label thereon from a place spaced from said support into position to deposit the label on an article to be labeled, and means for completing the

attachment of the label to the article while such device is returning to such place, said last mentioned means including a label pressing member, means supporting said member on said device for movement as a whole relative to said device, and means for moving said member to a position to engage the label on the article in pressure relation and for maintaining said member in such position during the return movement of said device to said place, said device and supporting means drawing said member while so maintained in such position progressively across the label during the return of the device to said place.

8. In a labeling machine, a support for an article to be labeled, a device having a label carrying surface and movable to carry a label thereon from a place spaced from said support into position to deposit the label on an article to be labeled, a label pressing member, means for supporting said member for movement relative to the label supporting surface of said device and toward and away from an article on said support, means for maintaining said member in a retracted position with relation to the label carrying surface of said device during the movement of said device to an article to be labeled, means for moving said device and said member while the latter is in retracted position to enable said device to deposit a label on the article to be labeled, and means for advancing said member past the label carrying surface of said device to a position between the latter and the support to engage the label on the article and for maintaining said member in such advanced position while moving the same across the label during the return movement of said device to said place.

9. In a labeling machine, a support for an article to be labeled, a device having a label carrying surface and movable at right angles to a surface of an article on said support into position to deposit a label on such surface, a label pressing member, means for supporting said member for movement relative to the label supporting surface of said device and toward and away from an article on said support, means for maintaining said member in a retracted position with relation to the label carrying surface of said device during the movement of said device to the article to be labeled, means for advancing said member relative to said device in substantially the same direction as the direction of label depositing movement of said device to a position to engage the label on the article, and means for moving said member in a direction substantially at right angles to the direction of the advancing movement thereof and lengthwise of the article surface on which the label is deposited, said advancing means and said moving means coacting to move said member while so maintained in such position progressively along the label on such article surface.

10. In a labeling machine, a support for an article to be labeled, a device having a label carrying surface and movable to carry a label thereon from a place spaced from said support into position to deposit the label on an article to be labeled and to return to said place after such deposition, a pressing device mounted on said label carrying device for pressing the label delivered to the article into firm contact with the latter and including a rotatably mounted roller and means supporting said roller for pivotal movement on said label carrying device, means for moving said pressing device in a direction substantially lengthwise of the article surface on which the label is to be deposited during the advancement of said label carrying device from said place to said position until the roller is beyond the portion of the article surface on which the label is deposited, means for pivoting said roller supporting means to bring said roller into label pressing position beyond the deposited label, and means for retracting said roller from its advanced position to roll the roller on the label under pressure in a direction substantially lengthwise of the article surface on which the label is deposited.

11. In a labeling machine, a support for an article to

be labeled, a device having a label carrying surface for delivering a label to an article on said support, a movable label pressing device, means for moving said pressing device from a retracted position and substantially lengthwise of the article surface on which the label is deposited to an advanced position where said pressing device is beyond the portion of such surface on which the label is deposited, means for moving said pressing device while in its advanced position toward said article surface to a label pressing position, said means being constructed and arranged to retract said pressing device from its advanced position in a direction lengthwise of the article surface on which the label is deposited while maintaining said pressing device in label pressing position, whereby the label is pressed on such article surface during such retraction of said pressing device.
